ELECTRICAL RELAY

Arthur E. Dodd, Edgewood, Pa., assignor to The Union Switch & Signal Company, Swissvale, Pa., a corporation of Pennsylvania

Application February 3, 1945, Serial No. 576,072

6 Claims. (Cl. 175—320)

1

My invention relates to electrical relays, and particularly to electrical relays of the direct current type having both a neutral and a polar armature. More particularly, my present invention relates to a relay of the type described suitable for use in railway signaling systems.

In certain applications of relays of the type described in railway signaling systems it is highly desirable in the interest of safety that the relay be provided with means to insure that the neutral armature will not pick up when the relay becomes energized until the polar armature agrees in position with the polarity of the energizing current, and one means for accomplishing this result is disclosed in Letters Patent of the United States No. 1,822,496, granted to Branko Lazich on September 8, 1931. Briefly described, this means comprises a pair of bucking windings mounted on extensions provided on the pole pieces of the main electromagnet. The extensions are so disposed that when the neutral armature swings away from the pole pieces of the main electromagnet, it will swing toward these extensions, whereby unless the bucking windings are energized by current of the proper polarity when the main electromagnet of the relay becomes energized, these pole piece extensions will cause the flux from the main electromagnet to exert a force on the neutral armature which holds it against the pole piece extensions. The bucking windings are arranged to be supplied with current usually from a local circuit over pole changing contacts controlled by the polar armature, and the parts are so proportioned that these windings will be energized by current of the proper polarity to cause the neutral armature to pick up when and only when the polar armature agrees in position with the polarity of the energizing current.

With a polar relay constructed in the manner outlined above, the voltages applied to the main and bucking windings must be maintained within certain limits with respect to each other, or the neutral armature will fail to pick up even though the polar armature agrees in position with the polarity of the energizing current. This is not objectionable for applications where the amount of line resistance is small because in these applications there is usually no difficulty in holding the voltages within the necessary limits. However, for applications where the line resistance is likely to be large, such for example, as is the case in signal control service, the limited operating range of the relay tends to limit its usefulness.

One object of my present invention is to provide an improved relay of the general type dis-

2

closed in the said Lazich Patent No. 1,822,496, which relay may be operated over wider limits of voltages and in a larger number of different circuit arrangements.

5 According to my invention, I accomplish this result, either by providing the relay with an auxiliary neutral armature and including in the energizing circuit for the bucking windings a contact controlled by this armature and closed only when this armature is picked up, or by including in the energizing circuit for the bucking windings a front contact of an auxiliary relay which is connected in series with the windings of the main electromagnet of the relay.

10 15 Other objects and characteristic features of my invention will become apparent as the description proceeds.

I shall describe two forms of relays embodying my invention, and shall then point out the 20 novel features thereof in claims.

In the accompanying drawings, Fig. 1 is a view, partly diagrammatic, showing one form of relay embodying my invention. Fig. 2 is a diagrammatic view showing another form of relay 25 embodying my invention.

Similar reference characters refer to similar parts in both views.

Referring first to Fig. 1, the relay in the form here shown comprises a core A consisting of three 30 parallel legs 1, 2 and 3 connected together at one end by a backstrap 4, and provided at the other end with pole pieces 5, 6 and 7, respectively. The middle leg 2 is a permanent magnet, but might, of course, equally well be a constantly energized 35 electromagnet; while the two outer legs 1 and 3 and the backstrap 4 are of ordinary magnetizable material.

The leg 1 is provided with a coil 1a and the leg 3 is provided with a coil 3a. The two coils 1a and 3a together comprise the operating winding of the relay and this winding is included in circuit with a battery B1 and a pole changer P comprising two contacts 8 and 9.

40 The pole piece 5 is provided with two extensions 5a and 5b, and the pole piece 7 is likewise provided with two extensions 7a and 7b. The extensions 5a and 7a, as shown in the drawings, extend laterally toward each other, but in actual practice these extensions project rearwardly from the pole pieces to a point opposite the middle leg 2, which latter leg is offset rearwardly from the legs 1 and 3. The extensions 5b and 7b are made U-shaped for a purpose which will appear presently, and are provided with coils 10 and 11, the 45 50 55 purpose of which will also appear presently.

The relay also comprises a main neutral armature 12, an auxiliary neutral armature 13 and a polar armature 14. The main neutral armature 12 is biased by gravity to a released position in which it rests on non-magnetizable stops 5c and 7c secured to the extensions 5b and 7b, respectively, but is adapted to be at times moved against the action of gravity to an attracted position in which the armature then engages non-magnetizable stops 5d and 7d provided on the under-side of the pole pieces 5 and 7, respectively. The neutral armature 12 controls a contact 15 which is closed or open according as this armature occupies its released or its attracted position.

The auxiliary neutral armature 13 is biased by gravity to a released position in which it is separated from the pole piece extensions 5a and 7a by means of air gaps, but is adapted to be moved, when the relay becomes energized, to a position in which it engages non-magnetic stops 5e and 7e secured to the pole piece extensions 5a and 7a, respectively. This armature controls a contact 16 which is open or closed according as it occupies its released or its attracted position.

The polar armature 14 is pivotally supported intermediate its ends by means of a pivot pin 17 between bifurcations which are formed in the pole piece 6, and is arranged to swing toward one or the other of the pole piece extensions 5a and 7a, non-magnetic stops 14a being attached to the armature to prevent the armature from coming into actual contact with the pole piece extensions. The polar armature 14 actuates two contact fingers 17 and 18 to close normal contacts 17-17a and 18-18a or reverse contacts 17-17b and 18-18b according as the armature is swung toward the pole piece extension 5a or the pole piece extension 7a.

The two coils 10 and 11 are connected in series in an energizing circuit which is supplied with current of normal or reverse polarity from a suitable source here shown as a battery B2, according as the normal contacts 17-17a and 18-18a or the reverse contacts 17-17b and 18-18b are closed. This energizing circuit includes the contacts 15 and 16 controlled by the armatures 12 and 13, and it will be obvious therefore that this circuit will become closed when and only when the polar armature occupies one or the other of its extreme positions, the main neutral armature 12 is released, and the auxiliary armature 13 is picked up. The two coils 10 and 11 function under certain conditions which will be made clear hereinafter to neutralize the flux which threads the pole piece extensions 5b and 7b due to the energization of the main coils 1a and 3a, and the coils 10 and 11 may, therefore, be collectively referred to as a bucking winding.

As shown in the drawing, pole changer P is in its normal position, so that current of what I shall term "normal polarity" is being supplied to the coils 1a and 3a. Under these conditions, the polar armature 14 will occupy its normal position in which it is shown in the drawing, and the main and neutral armatures 12 and 13 will both be picked up. With the neutral armature 12 in its picked up position, the circuit for the bucking coils 10 and 11 is open at contact 15, and these coils are therefore deenergized.

I will now assume that pole changer P is reversed, thereby reversing the polarity of the current supplied to the main operating coils 1a and 3a. The reversal of the current in these coils will cause the flux threading the armature 12 to decrease to zero, and when this happens this ar-

mature will release due to its gravity bias. As soon as armature 12 releases, the reluctance of the flux path from the pole pieces 5 and 7 to the armature by way of extensions 5b and 7b will become less than the reluctance of the flux path from the pole pieces 5 and 7 to the armature by way of the air gaps between the pole pieces and the armature and, consequently, as the flux builds up in the reverse direction in the legs 1 and 3, it will exert a hold-down torque on the armature 12 until such time as the coils 10 and 11 become energized to neutralize the flux in the extensions 5b and 7b. The reversal of the flux in the cores 1 and 3 will also cause the polar armature 14 to reverse, and the armature 13 to release and again pick up. The reversal of the polar armature 14 will open the normal polar contacts 17-17a and 18-18a and close the reverse polar contacts 17-17b and 18-18b and, consequently, when the armature 13 picks up and closes the front contact 16, the coils 10 and 11 will become energized by current of reverse polarity. The coils 10 and 11 are disposed on the extensions 5b and 7b in such manner that when these coils are energized by current of the same relative polarity as that which is being supplied to the coils 1a and 3a the fluxes set up in the extensions 5b and 7b by the two sets of coils will neutralize each other; and the parts are so proportioned that the armature 13 will not pick up until the flux induced in the legs 1 and 3 by the energization of coils 1a and 3a has built up to the value necessary to cause the armature 12 to pick up with the flux in the extensions 5b and 7b neutralized. It will be seen, therefore, that the picking up of the armature 12 under the conditions just described is delayed until after the auxiliary armature 13 picks up. When the armature 12 picks up the resultant opening of the contact 15 deenergizes the coils 10 and 11 to thereby save energy.

When the pole changer P is restored to its normal position, the main energizing coils 1a and 3a will again receive current of reverse polarity. This will cause both neutral armatures 12 and 13 to release and the polar armature 14 to return to the normal position shown. The return of the polar armature to its normal position will open the reverse polar contacts 17-17b and 18-18b and will close the normal polar contacts 17-17a and 18-18a, and as a result, as soon as the neutral armature 13 again picks up, the bucking winding will receive current of normal polarity. Since the main and bucking windings will then both be receiving current of normal polarity, the fluxes induced in the extensions 5b and 7b by these windings will again neutralize each other, and the main armature will therefore pick up and will open the contact 15 thereby deenergizing the bucking winding.

I will now assume that with the parts in the position shown in the drawing pole changer P is reversed, but that the polar armature 14 fails to reverse in response to the reversal in the polarity of the current supplied to the operating coils 1a and 3a. Under these conditions when the neutral armature 13 picks up, the bucking winding will be supplied with current of normal polarity, and since this current is of the opposite relative polarity to that supplied to the main winding, the effect of the bucking winding will be to induce in the extensions 5b and 7b a flux which assists that due to the current in the main winding. As a result, the neutral armature 12 will now be held in its released position against the non-magnetic stops 5c and 7c. The same result will occur

if the polar armature P fails to move to its normal position when it occupies its reverse position and the pole changer P is operated to cause the coils 1a and 3a to be supplied with current of normal polarity.

Referring now to Fig. 2, in the modified form of my invention here shown, I employ, in place of the front contact 16 controlled by the auxiliary neutral armature 13 for delaying the application of energy to the bucking winding until the flux in the main winding has built up to the value at which it is desired to have the armature 12 pick up, the front contact 26 of an auxiliary relay C the energizing winding of which is connected in series in the energizing circuit for the coils 1a and 3a. This relay is so adjusted that it will close its front contact 26 when the current in the coils 1a and 3a has increased to approximately the same value at which the armature 13 picks up and closes the contact 16 in the form of the relay shown in Fig. 1, and it follows, therefore, that the relay combination shown in Fig. 2 will operate in essentially the same manner as the relay shown in Fig. 1.

It will be seen from the foregoing that in both forms of relays embodying my invention I have provided means for delaying the application of energy to the bucking winding until the flux in the main winding has built up to approximately the value at which it is desired to have the main neutral armature 12 picked up. As a result, when energy is applied to the bucking winding, the main neutral armature 12 will pick up as soon as the flux induced in the bucking winding has built up to the value at which it neutralizes the main coil flux in the extensions 5b and 7b. This causes the pick-up value of the main neutral armature 12 to become practically independent of the voltage applied to the bucking winding so long as sufficient energy is supplied to this winding to always insure that the flux due to the bucking coils will be able to neutralize the main coil flux which threads the polar extensions 5b and 7b.

It will also be seen that the use of the auxiliary armature or the series relay serves to delay the application of energy to the bucking winding in the desired manner under direct pick-up conditions as well as when the energizing circuit is pole changed, and in addition provides a means for deenergizing the bucking winding when the main winding is deenergized. The fact that the bucking winding is deenergized when the main winding is deenergized results in a savings in power over the form of relay described in the Lazich Patent No. 1,822,496, referred to hereinbefore.

One advantage of a relay constructed in accordance with my invention is that it permits the relay to be operated over a wider range of voltages and in a larger number of different circuit arrangements than has heretofore been possible with polar relays which are provided with a means for positively checking that the position of the polar armature corresponds to the polarity of the energizing current supplied to the main coils before it is possible for the neutral armature to pick up.

Although I have herein shown and described but two forms of electrical relays embodying my invention, it is understood that various changes and modifications may be made therein within the scope of the appended claims without departing from the spirit and scope of my invention.

Having thus described my invention, what I claim is:

1. A relay comprising an operating winding and a bucking winding, a polar armature responsive to the polarity of the current in said operating winding, a neutral armature, means for picking up said neutral armature when and only when said operating and bucking windings are both supplied with current and the current in said bucking winding is of the same relative polarity as the current in said operating winding, means controlled by said polar armature for controlling the polarity of the current supplied to said bucking winding, and means for delaying the energization of said bucking winding when said operating winding becomes energized until the current in the operating winding has built up to the desired pick-up value for the neutral armature.

2. A relay comprising an operating winding, a polar armature responsive to the polarity of the current in said operating winding, a main and an auxiliary neutral armature both responsive to the presence and absence of current in said winding, and means for preventing said main neutral armature from picking up unless said polar armature occupies a position corresponding to the polarity of the current being supplied to said winding and said auxiliary neutral armature has picked up.

3. A relay comprising an operating winding, a polar armature responsive to the polarity of the current in said operating winding, a neutral armature responsive to the presence or absence of current in said operating winding, a contact, means for closing said contact when and only when said operating winding is energized to a predetermined extent sufficient to pick up said neutral armature, and means controlled in part by said contact for preventing said neutral armature from closing unless said polarized armature occupies a position corresponding to the polarity of the current being supplied to said winding.

4. A relay comprising a core provided with pole pieces, an operating winding on said core, a polarized armature cooperating with said pole pieces and responsive to the polarity of the current in said winding, pole piece extensions secured to said pole pieces, a first neutral armature movable between said pole pieces and said pole piece extensions and biased toward said pole piece extensions, a bucking winding on said pole piece extensions, a second neutral armature cooperating with said pole pieces and responsive to the presence or absence of current in said operating winding, and means for supplying current of normal or reverse relative polarity to said bucking winding when and only when said second neutral armature is picked up according as said polarized armature is in its normal or its reverse position, the parts being so arranged that unless said polarized armature occupies the position corresponding to the polarity of the current being supplied to said operating winding said bucking winding will assist the operating winding in holding said first neutral armature against the pole piece extensions but that when the polarized armature occupies the position corresponding to the polarity of the current being supplied to the operating winding the bucking winding will oppose the flow of flux through said extensions so that said first neutral armature will move toward said pole pieces.

5. A polar relay comprising an operating winding adapted to be reversibly supplied with current, a polarized armature responsive to the po-

larity of the current in said operating winding, a neutral armature responsive to the presence and absence of current in said winding, an auxiliary relay connected in series with said operating winding, and means effective when the polarity of the current supplied to said operating winding is reversed for preventing said neutral armature from closing unless said polarized armature occupies the position corresponding to the polarity of the current being supplied to said winding and said auxiliary relay is energized to a predetermined extent.

6. A polar relay comprising an operating winding, a polarized armature responsive to the polarity of the current in said operating winding, a neutral armature responsive to the presence and absence of current in said winding, an auxiliary relay connected in series with said operating winding and provided with a contact which becomes closed when and only when said auxili-

ary relay is energized to a predetermined extent, and means for preventing said neutral armature from closing unless said polarized armature occupies the position corresponding to the polarity of the current being supplied to said winding and said contact is closed.
